ATTORNEYS

UNITED STATES PATENT OFFICE.

JAMES H. MILLHOLLAND, OF PHILADELPHIA, PENNSYLVANIA, ASSIGNOR TO JOHN S. CLEMENT COMPANY, INC., OF PHILADELPHIA, PENNSYLVANIA, A CORPORATION OF PENNSYLVANIA.

FLOOR WAXER.

Application filed August 7, 1925. Serial No. 48,744.

My invention consists in an improved device adapted particularly for intermittently feeding liquid wax from an attached container and conveniently spreading the same upon a floor preparatory to polishing; and the novel and advantageous construction thereof is hereinafter fully set forth in connection with the accompanying drawing, and clearly defined in the subjoined claims.

10 Fig. 1 is a central longitudinal sectional elevation of a device embodying my invention in preferred form; an attached wax container or reservoir being indicated in dotted lines.

15 Fig. 2 is mainly a plan view of the same, indicating also the casing-connected handle; the valve being removed and a portion of the casing being broken away so as to reveal the enclosed brush back.

20 The drawing indicates an ordinary brush having a wood back 10; the middle bristles however being omitted, in line with a circular aperture 11 provided in the back; and the latter being provided with spaced apart

25 screw-posts 12, 12, by means of which the casing 15, hereinafter fully described, is movably secured to the back with springs 13, 13 interposed so as to normally maintain the casing at a determined height above

30 the brush back.

The casing 15 is very economically and satisfactorily made of die-shaped sheet metal. It comprises rectangular end and side walls 16 and 17 which loosely fit the brush back 10; a top plate 18 the intermediate portion of which is cupped so as to form a funnel-shaped portion 19 depending loosely into the aperture 11; and a hollow upward extension 20 concentric with the funnel portion 19 and forming in connection with the latter a discharge chamber 21, through which, and the aperture 11, liquid wax is delivered to the floor under treatment. This upward extension 20 of the casing, which is separately die-shaped and rigidly attached to the latter as indicated, has its circular wall so formed as to tightly engage the mouth of a removable liquid-wax container or reservoir indicated at 25 in dotted lines;

45 while its closure plate 26 is formed with a

central opening forming a depressed valve seat 27.

The valve 30 is provided with a stem 31 extending downward through the discharge chamber 21 into the back aperture 11. The 55 valve is normally seated by a stem-enclosing spring 32 pressing against a fixed collar 33. As shown, the notched lower end 34 of the stem however engages a supporting bar 35 provided in the lower portion of the back 60 aperture 11; a bent wire secured to the back 10, conveniently forming such supporting bar, and serving to maintain the valve 30 at a fixed height above the brush regardless 65 of any relative downward movement imparted to the casing.

The liquid wax may be contained in the can 25 in which it is conveniently salable; the mouth 25^a thereof being adapted to tightly fit upon the casing extension 20 so 70 that when the can is in inverted position upon the casing it serves as a reservoir under control of the valve 30. As indicated the can is steadied and tightly held upon the casing 15 by means of a bail 38 pivotally 75 connected to the latter; and a handle 36—37 is also pivotally connected to the casing so as to conveniently serve both for moving the brush to spread the fed liquid, and for intermittently pressing the casing downward 80 upon the brush to effect the feeding. This relative movement of the casing upon the brush compresses the valve spring 32 without changing the position of the valve 30 relative to the brush which supports it by 85 means of the cross-bar 35, so that the liquid is permitted to flow downward through the casing chamber 21 and brush-back aperture, 11, to the floor, until the downward pressure upon the casing is removed. The construction of the device is as simple as its 90 operation and very inexpensive.

What I claim is:

1. In a floor waxer comprising a brush having an apertured back; a relatively movable casing having a yielding connection to the brush back and said casing being provided with a valved discharge chamber forming a tapered reservoir-attaching upward projection thereon and a depending 100

aperture-communicating funnel slidable in said aperture; and a valve spring-seated in the top closure plate of said reservoir-attaching projection and having a depending stem in said chamber supported by the brush back below said depending funnel.

2. In a floor waxer comprising a brush having an apertured back; a movably attached sheet-metal casing on said back, hav-

ing a discharge chamber with a depending 10 funnel portion slidable in said aperture and a valved upward extension of tapering form adapted for supporting a separate liquid reservoir, said casing having pivoted there- 15 to an operating handle and reservoir retaining means.

In testimony whereof I affix my signature.

JAMES H. MILLHOLLAND.
